FASTENING INSERTING MACHINE

Fred N. La Chapelle, Beverly, Mass., assignor to
 United Shoe Machinery Corporation, Borough
 of Flemington, N. J., a corporation of New
 Jersey

Application September 10, 1938, Serial No. 229,233

14 Claims. (Cl. 1—19)

This invention relates to fastening inserting machines and is illustrated herein by way of example as embodied in a machine arranged to insert fiber fastenings in shoes.

An object of the invention is to provide in a machine of the type referred to improved means for adapting the machine for use in inserting fastenings across the forward portion of a heel on a shoe adjacent to the breast of the heel.

10 To the attainment of this object the invention provides, in accordance with one feature, improved means for supporting a shoe while it is moved transversely of the fastening inserting instrumentalities of the machine to permit said instrumentalities to insert fastenings across the forward portion of a heel on the shoe adjacent to the breast of the heel, said means, as herein illustrated, comprising a plate of substantial width mounted on a work support or spindle 15 which is normally arranged to swing relatively to the fastening inserting instrumentalities about axes located forwardly of said instrumentalities to permit the shoe to be turned while fastenings are inserted around the sides and back of the heel. The shoe is moved across the plate while fastenings are inserted along the breast of the heel and is supported by the plate during the inserting operation.

20 In accordance with another feature of the invention, improved means is provided for guiding the shoe during both the insertion of fastenings around the sides and back of the heel and across its breast, this means, as herein illustrated, comprising a pair of gages arranged to be moved separately into and out of operative position, the heel breast gage being arranged to engage the breast of the heel forwardly of the driving instrumentalities but rearwardly of the axes about which the work support swings.

25 Any tendency by reason of this arrangement for the work support to swing inwardly during the insertion of fastenings across the breast of the heel and move the shoe away from the heel breast gage is effectively prevented by means which forms another feature of the invention. As illustrated herein, this means comprises a removable locking pin arranged to be inserted into holes in the work support and a portion of the machine which holds the work support 30 and is fixed with respect thereto, these holes being in alignment when the work support is in a proper position for supporting the shoe while the heel breast fastenings are being inserted.

35 With the above and other objects and features in view, the invention will now be described

with reference to the accompanying drawings and will thereafter be pointed out in the claims.

In the drawings,

Fig. 1 is a side elevation of a machine embodying the present invention with parts broken away and in section; 5

Fig. 2 is an enlarged plan view of the work support and gages forming a part of the invention, one gage being shown engaging the breast of a heel on a shoe; 10

Fig. 3 is an enlarged side elevation of the work support and gages, the gages being shown in the same position as in Fig. 2;

Fig. 4 is a plan view of the gages in the positions they occupy when guiding the sides and back of the heel; and 15

Fig. 5 is a side elevation similar to Fig. 3 with the gages shown in the same position as in Fig. 4.

The illustrated embodiment of the invention is shown herein as applied to a fastening inserting machine of the general type disclosed in Letters Patent of the United States No. 1,587,848, granted June 8, 1926, on an application filed in the name of Fred L. MacKenzie but with the pawl and ratchet mechanism of the horn release 20 modified as shown in United States Letters Patent No. 1,686,808, granted October 9, 1928, on an application filed in the names of George Goddu and Fred L. MacKenzie, the machine being further modified to adapt it for inserting fiber 25 fastenings instead of loose nails, as disclosed in Letters Patent of the United States No. 1,849,253, granted March 15, 1932, on an application filed in the name of Fred N. La Chapelle. Reference may be had to the patents mentioned for such 30 parts of the machine as it is unnecessary to illustrate herein.

The machine is provided with a column 10 which supports at its upper end a head 12 provided with fastening inserting instrumentalities 40 indicated generally in Fig. 1 by the numeral 14 and including an awl 16 and a driver (not shown) arranged to punch a hole in the work being operated upon, to feed the work into alignment with the driver, and to drive a fastening 45 into the hole. The fastening is composed of fibrous material, such as paper, twisted and treated to form a stiff peg, this material being carried by a reel 18. The awl and driver are cam operated, as disclosed in the Goddu et al. Patent 50 No. 1,686,808 above referred to, and the fastenings are cut and delivered to a nozzle or throat movable into line with the driver in the manner disclosed in the La Chapelle Patent No. 1,849,253. The head of the machine is also provided with 55

a presser plate or abutment 20 against which the work is clamped during the fastening inserting operation.

As disclosed in the MacKenzie Patent No. 1,587,848, the column 10 also carries a work support comprising a post 22 mounted for vertical movement in an upstanding portion 24 of the column 10 and having secured to its upper end a supporting bracket 26 which extends downwardly and has attached to its lower end a casing 28. The casing carries a slide 30 upon which is mounted for rocking movement transversely of the machine a member 32 and upon which is pivoted on a horizontal pin 34 a spindle 36 which can swing inwardly and outwardly with respect to the machine head about the pivot 34.

The work support or jack, including the spindle 36, is arranged to be moved upwardly by a treadle 38 to bring the work, such as a shoe A, into engagement with the abutment 20 to measure the thickness of the work, the work support being then locked in this upper position by mechanism contained in the casing 28 and fully disclosed in the MacKenzie Patent No. 1,587,848. Continued depression of the treadle 38 causes it to become disconnected from the measuring and locking mechanism and to operate further mechanism, contained within the column 10 and indicated generally in Fig. 1 by the reference numeral 40, to raise the post 22 and press the shoe against the abutment 20 under the force of a spring 42, thereby clamping the work during the operation of the fastening inserting instrumentalities. The mechanism 40 then operates automatically to release the shoe from the abutment 20 to permit the awl to feed the same after which the mechanism clamps the work again before another fastening is driven. This mechanism for causing the work support to clamp and release the work during the fastening inserting operation is fully disclosed in the Goddu et al. Patent No. 1,686,808 referred to above.

The present machine is adapted to insert fastenings formed from fibrous material around the sides and back of a heel on a shoe and also to insert fastenings across the forward portion of the heel adjacent to its breast to complete the attachment of the heel to the shoe, this operation being sometimes referred to as "slugging" the heel on the shoe. It will be obvious that when the machine is inserting fastenings around the sides and back of a heel B, which may be composed of either leather or rubber, the work support 36 must be free to swing relatively to the fastening inserting instrumentalities to permit the shoe to be turned into positions in which the fastenings can be inserted around the periphery of the heel, as shown in Fig. 4. Free swinging movement of the work support 36 transversely of the machine is permitted by the member 32 and swinging movement inwardly and outwardly of the machine is permitted by the pivot 34. Accordingly, when slugging around the sides and back of the heel, the operator is able to swing the work support both lengthwise and transversely of the fastening inserting instrumentalities and thus control the positions of the fastenings inserted around such portions.

When performing this operation the work support is provided at its upper end with the usual last pin 44 (Figs. 4 and 5) for holding the last and shoe, this pin being removably secured on the spindle 36 by a leaf spring 46. As shown in Figs. 3 and 5, the upper end of the spindle 36 is provided with ears 48 between which is mounted on

an eccentric pin 50 a holding member 52 provided at its lower end with ratchet teeth 54 arranged to engage with teeth on a member 56 fixed to the support 36 whereby the holding member 52 may be adjusted to vary its angle relatively to the spindle 36. Since this mechanism is well known in the art, a further description of it need not be given herein. When fastenings are being inserted around the sides and back of the heel B, therefore, the shoe A, which is mounted on a last 10 C, is supported by the engagement of the last pin 44 in the hole or thimble in the heel end of the last, as shown in Figs. 4 and 5.

In order that the fiber fastenings, which are indicated in Fig. 4 by the numeral 58, will be located 15 a proper distance from the periphery of the heel B, the machine is provided with a gage 60 arranged to engage the edge face of the heel around its sides and back and maintain the heel in the proper position relatively to the fastening inserting 20 instrumentalities during the fastening inserting or slugging operation. The gage 60 is adjustably mounted on an arm 62 whereby the gage may be adjusted lengthwise for shoes of different 25 sizes and it is held in adjusted position by a screw 64. The arm 62 has a hub portion 65 rotatably mounted on a shaft 66 (Fig. 2) supported in a horizontal bracket 68 having a plate-like portion 69 secured by screws 70 to the under side of the machine head some distance rearwardly of the 30 fastening inserting mechanism 14. The hub 65 of the arm 62 has a pin 72 secured in an opening therein and projecting inwardly beyond the hub, the pin having a rounded end adapted to enter either one of two depressions 74, 76 formed in the 35 surface of the bracket 68 abutting the hub and located so that when the pin is seated in the depression 74 the gage 60 is in operative position, as shown in Figs. 4 and 5. The hub 65 is urged yielding against the bracket 68 by a spring 78 surrounding a spacing bushing or collar 80 slidably mounted on the shaft 66, the spring and bushing being retained on the shaft 66 by a nut 82 threaded on the end of the shaft. The bushing 80 is somewhat shorter than the space between 45 the outer surface of the hub and the inner side of the nut 82 so that it allows the arm to be rotated about the shaft 66 to cam the pin 72 out of the depression 74 against the force of the spring and to be swung downwardly into the position shown 50 in Fig. 3, in which position the pin 72 snaps into the other depression 76 and maintains the arm and gage 60 in an inoperative position away from the shoe. It will be seen from the foregoing that when the gage 60 is engaging the edge face of the 55 heel B for guiding the shoe while fastenings are being inserted around the sides and back of the heel, the downward force or pressure of the driving instrumentalities 14 tends to swing the work support 36 inwardly about the pivot 34 to hold the 60 shoe in firm engagement with the gage 60 when a fastening is driven. In other words, since the pivot 34 is located forwardly of the line of drive, the driving action tends to swing the jack inwardly about the pivot 34 and thus press the heel 65 firmly against the gage 60 which is located inwardly of the driving instrumentalities 14.

When it is desired to insert fastenings across the front portion of the heel B adjacent and parallel to the breast 84 of the heel, the shoe must 70 be moved transversely of the machine relatively to the fastening inserting instrumentalities and, since the fastenings are positioned and inserted with reference to the breast of the heel, the shoe must be guided from said heel breast. The means 75

for supporting the shoe and permitting movement thereof transversely of the fastening inserting instrumentalities comprises a relatively wide plate 86 (Figs. 1 to 3, inclusive) which may be removably secured to the holding member 52 of the work support 36 in the same manner as the last pin 44 was secured thereto by a pin 88 entering a hole in the member 52 and being retained in the hole by the spring 46 engaging a projection 90 extending laterally from the pin 88. The plate 86, as shown in Fig. 2, is of sufficient width to permit the heel portion of the last C to rest thereon and be moved across the surface of the plate transversely of the machine to locate the shoe in proper positions for the insertion of fastenings across the entire breast of the heel.

In order to guide the shoe while the fastenings are being inserted across the breast of the heel the machine is provided with a heel breast gage 92 secured for lengthwise adjustment on an arm 94 by a screw 95, the arm having a hub portion 96 thereon (Figs. 2 and 4) which is rotatably mounted on the shaft 66 at the end of the bracket 68 opposite the end at which the arm 62 is located. The hub 96 carries a pin 98 having a rounded end adapted to enter each of two depressions or holes 100, 102 formed in the surface of the bracket 68 abutting the hub, this arrangement causing the arm 94 and gage 92 to be located in operative position when the pin is engaging the hole 100 (Figs. 2 and 3) and to be located in an inoperative position away from the shoe when the pin is engaging the depression 102, as shown in Figs. 4 and 5. The spring 78 permits movement of the hub 96 lengthwise of the shaft 66 to cause the pin 98 to be cammed out of one hole by rotation of the hub and to snap into the other hole as the arm and gage are moved from operative to inoperative position or vice versa.

It will be seen from Figs. 2 and 3 that the gage 92 projects forwardly of the fastening inserting instrumentalities in order to engage the breast of the heel. Accordingly, the pressure of the fastening inserting operation against the plate 86 and work support 36 will tend to swing the work support inwardly about the pivot 34 and thus move the heel away from the breast gage 92 if the work support were free to swing about that pivot during the fastening inserting operation. In order to prevent swinging movement of the work support and to insure that the shoe can always be held firmly by the operator against the gage 92 when slugging across the breast of the heel, the machine is provided with means for locking the work support against swinging movement during the insertion of fastenings across the heel breast. At its lower portion the work support 36 is provided with a projection 108 through which is bored a relatively large hole 110 which is substantially parallel to the adjacent upstanding portion of the work support. Bolted to the slide 30 by a pair of bolts 112 is a bracket 114 having a hole 116 formed therein the same size as the hole 110 in the work support and located at such an angle that the hole 110 will be in alinement with the hole 116 when the work support is in a proper angular position for supporting the shoe while slugging across the breast of the heel. In other words, when the plate 86 is in a position to support the last C directly under the fastening inserting instrumentalities so that the shoe may be supported under the line of drive, the holes 110 and 116 are in alinement with each other. The casting 114 is further se-

cured to the slide 30 by a clamping plate 118 arranged to engage the inner side of the slide and provided with forwardly extending bolts 120, 122 which pass through the hole 116 and have nuts 124, 126 threaded on their outer ends.

Secured by a chain 128 or other suitable means to a lower portion of the machine frame is a locking pin 130 which is arranged to fit slidingly into the holes 110 and 116 when they are in alinement and thereby lock the work support 36 rigidly against swinging movement while fastenings are being inserted across the breast of the heel. The locking pin 130 is provided at its lower end with a slot 132 (Fig. 3) which permits the pin to be inserted in the hole 116 without interference with the clamping bolts 120, 122 which pass therethrough, the bolt 122 engaging the upper end of the slot 132 and preventing the pin from dropping out of the holes. Accordingly, when inserting fastenings across the breast of the heel the locking pin 130 will be inserted into the holes 110 and 116 and the work support 36 will be locked rigidly in its operative position.

In operating the machine it is preferable to insert the fastenings 58 around the sides and back of the heel with the shoe held on the support by the last pin 44 and with the work support free to swing in two directions to permit the heel to be maintained against the edge gage 60 to locate the fastenings properly with respect to the edge face of the heel. After this operation has been performed on one shoe or, if desired, on a number of shoes, the edge gage 60 may be moved from its operative position into the idle position shown in Fig. 3, and the heel breast gage 92 may be moved into its operative position. The last pin 44 is removed from the work support and replaced by the supporting plate 86 and the spindle is swung into a position in which the hole 110 is in alinement with the hole 116. The locking pin 130 is then inserted into these holes to lock the work support rigidly in operative position. The heel portion of the last C is placed on the plate 86 and moved across the same transversely of the machine while the fastening inserting instrumentalities insert as many fastenings 134 as are desired across the forward portion of the heel adjacent to its breast. The rigid condition of the work support 36 enables the operator to maintain the breast of the heel against the gage 92 without difficulty while inserting the fastenings 134, the last and shoe being moved across the plate 86 by the feeding movement of the awl 16.

Having thus described my invention, what I claim as new and desire to secure by Letters Patent of the United States is:

1. In a fastening inserting machine, the combination with fastening inserting instrumentalities and means for operating the same, of a work support arranged normally to swing relatively to said instrumentalities, means removably secured to the upper end of said work support for supporting a shoe while a plurality of fastenings are inserted successively across a heel on the shoe adjacent to the breast of the heel, and means for preventing swinging movement of the work support throughout the period during which said fastenings are being inserted.

2. In a fastening inserting machine, the combination with fastening inserting instrumentalities and means for operating the same, of a work support normally arranged to swing lengthwise and transversely of the machine relatively to said instrumentalities, means mounted on said work

- support for supporting the rear portion of a shoe while fastenings are inserted across a heel on the shoe adjacent to its breast, said means comprising a plate of sufficient size to support the shoe 5 while it is moved along the plate transversely of the machine to permit fastenings to be inserted across the entire width of the breast of said heel, and means for preventing swinging movement of the work support only while said fastenings 10 are being inserted.
3. In a fastening inserting machine, the combination with fastening inserting instrumentalities and means for operating the same, of a work support arranged normally to swing relatively to 15 said instrumentalities, means carried by the upper end of said work support and extending widthwise of the machine beyond said upper end for supporting a shoe while fastenings are inserted successively across a heel on the shoe adjacent to the breast of the heel, and means for locking the work support against swinging movement during the insertion of said fastenings, said means comprising a member separate from said work support constructed and arranged to connect the work support to a portion of the machine that is fixed with respect to said support. 20
4. In a fastening inserting machine, the combination with fastening inserting instrumentalities and means for operating the same, of a work support, mechanism arranged to support said work support for swinging movement relatively to said instrumentalities, means mounted on said work support for supporting a shoe while fastenings are inserted widthwise of a heel on the 25 shoe adjacent to the breast of the heel, and means for preventing swinging movement of the work support only during the insertion of said fastenings, said means comprising a locking pin arranged to be inserted through a hole in said work support and to extend into another hole in said supporting mechanism.
5. In a fastening inserting machine, the combination with fastening inserting instrumentalities and means for operating the same, of a work support arranged to swing relatively to said instrumentalities to permit fastenings to be inserted around the sides and back of a heel on a shoe, means mounted on said support for supporting the shoe while fastenings are inserted across the width of the heel adjacent to its breast, and means for preventing swinging movement of the work support while the last-named fastenings are being inserted. 30
6. In a fastening inserting machine, the combination with fastening inserting instrumentalities and means for operating the same, of a work support arranged to swing relatively to said instrumentalities, a gage arranged to engage the edge face of a heel on a shoe and guide the shoe 35 while fastenings are inserted around the sides and back of the heel, means carried by said work support for supporting the shoe while fastenings are inserted across the heel adjacent to its breast, and means for preventing swinging movement of the work support while said last-named fastenings are being inserted. 40
7. In a fastening inserting machine, the combination with fastening inserting instrumentalities and means for operating the same, of a work support arranged to swing in directions to permit fastenings to be inserted around the sides and back of a heel on a shoe parallel to the edge face of the heel, means mounted on said work support for supporting the shoe while fastenings 45 are inserted across the heel adjacent to its breast, 50

and means for engaging the heel and controlling the positions of the last-named fastenings relatively to said breast.

8. In a fastening inserting machine, the combination with fastening inserting instrumentalities and means for operating the same, of a work support arranged to swing in two directions to permit fastenings to be inserted around the sides and back of a heel on a shoe parallel with the edge face of the heel, means mounted on said work support for supporting the shoe while fastenings are inserted across the heel adjacent to its breast, a gage for determining the positions of the fastenings inserted across the breast of the heel relatively to said breast, and means for preventing swinging movement of the work support while said last-named fastenings are being inserted. 10

9. In a fastening inserting machine, the combination with fastening inserting instrumentalities, and means for operating the same, of a work support arranged to swing relatively to said instrumentalities to permit fastenings to be inserted around a heel on a shoe adjacent to the sides and back of the heel, means on said support 15 for supporting the shoe while fastenings are inserted transversely of the heel adjacent to its breast, a gage for guiding the shoe while fastenings are inserted around the sides and back of the heel, and another gage for guiding the shoe 20 while fastenings are inserted transversely of the heel adjacent to its breast.

10. In a fastening inserting machine, the combination with fastening inserting instrumentalities and means for operating the same, of a work support arranged to swing relatively to said instrumentalities to permit fastenings to be inserted around a heel on a shoe adjacent to the sides and back of the heel, means on said support 25 for supporting the shoe while fastenings are inserted transversely of the heel adjacent to its breast, a gage for guiding the shoe while fastenings are inserted around the sides and back of the heel, another gage for guiding the shoe while fastenings are inserted adjacent to the breast of the heel, and means for locking the work support 30 against swinging movement only while said last-named fastenings are being inserted. 35

11. In a fastening inserting machine, the combination with fastening inserting instrumentalities and means for operating the same, of a work support arranged to swing relatively to said instrumentalities to permit fastenings to be inserted around a heel on a shoe adjacent to the sides and back of the heel, means on said support 40 extending widthwise of the machine for supporting the shoe while fastenings are inserted transversely of the heel adjacent to its breast, a gage for guiding the shoe while fastenings are inserted around the sides and back of the heel, another gage separate from said first-named gage for guiding the shoe while fastenings are inserted adjacent to the breast of the heel, said gage being arranged when in operative position to extend forwardly of the heel in a position to engage 45 its breast when said breast is located widthwise of the machine, and means for holding each gage out of operative position when the other gage is operating. 55

12. In a fastening inserting machine, the combination with fastening inserting instrumentalities and means for operating the same, of a work support arranged to swing about horizontal axes located forwardly of said instrumentalities to permit fastenings to be inserted around a heel on a 60

shoe adjacent to the sides and back of the heel, a plate carried by said work support for supporting the shoe while fastenings are inserted across the heel parallel to its breast, a gage for guiding the shoe while fastenings are inserted around the sides and back of the heel, another gage arranged to engage the breast of the heel and guide the shoe on said plate while fastenings are inserted across the breast of the heel, said gages being arranged to be moved separately into and out of operative position, and spring means for holding one gage in its operative position and the other gage in its inoperative position and vice versa.

13. In a fastening inserting machine, the combination with fastening inserting instrumentalities and means for operating the same, of a work support arranged to swing inwardly and outwardly and transversely relatively to said instrumentalities to permit fastenings to be inserted around a heel on a shoe adjacent to the sides and back of the heel, means carried by said support for supporting the shoe while fastenings are inserted across the forward portion of the heel adjacent to its breast, a gage for guiding the shoe while fastenings are inserted around the sides and back of the heel, another gage for guiding the shoe while fastenings are inserted across the breast of the heel, means for holding one gage in operative position while the other gage is in an inoperative position and vice versa, and means for adjusting said gages relatively to said instrumentalities to

adapt them for operating on shoes of different sizes.

14. In a fastening inserting machine, the combination with fastening inserting instrumentalities and means for operating the same, of a work support arranged to swing in two directions about axes located out of alignment with said instrumentalities to permit fastenings to be inserted in the heel of a shoe around the sides and back of the heel, a gage arranged to engage the edge face of said heel and guide the shoe while fastenings are inserted around the sides and back of the heel, said gage being so positioned that pressure of the fastening inserting instrumentalities on the heel tends to swing the work support and shoe against the gage, means carried on said support for supporting the shoe while it is moved transversely of said instrumentalities to permit fastenings to be inserted across the heel adjacent to its breast, another gage arranged to engage the breast of the heel and guide the shoe while fastenings are inserted across the breast of said heel, said gage being so positioned that pressure from the fastening inserting instrumentalities tends to swing the work support and heel away from the heel breast gage, and means for preventing swinging movement of the work support only during the insertion of fastenings across the breast of the heel.

FRED N. LA' CHAPELLE. 30
